UNITED STATES PATENT OFFICE.

REGINALD FRANCIS HALLIWELL, OF LEAMINGTON SPA, ENGLAND, ASSIGNOR TO GENERAL ELECTRIC COMPANY, A CORPORATION OF NEW YORK.

ELASTIC-FLUID TURBINE.

Application filed June 1, 1921, Serial No. 474,144, and in Great Britain June 7, 1920.

The present invention relates to elastic-fluid turbines and more particularly to turbines used for marine propulsion and which comprise an ahead section and a reversing section mounted on the same shaft. In such turbines, when one section is rotating in its forward direction and doing work, the other section is idle and is rotated backwards in dead steam. A considerable amount of heat is generated by the friction caused by the blades of the idle running rotor, rotating in the dead steam, there being danger of the rotor and blading thereon reaching dangerously high temperatures under these conditions.

The object of the present invention is to provide, in connection with a turbine of the above type, an improved structure and arrangement for effecting a cooling of the idle running turbine rotor, when running backwards, and for a consideration of what I believe to be novel and my invention, attention is directed to the accompanying description and the claims appended thereto.

In the drawing, Fig. 1 is a diagrammatic view of a turbine arrangement embodying my invention, and Fig. 2 is a sectional view of a modification.

Trouble from overheating is more particularly experienced in the case of compound turbines; that is, turbines comprising a high pressure section and a low pressure section mounted in separate casings, and in the present instance I have particularly illustrated my invention in connection with a turbine of this type. It is to be understood, however, that this is only by way of example, and that the invention is not necessarily limited thereto.

Referring to the drawing, 5 indicates a high pressure turbine having an ahead section 6 and a reversing section 7. A partition wall 8 separates the ahead section of the turbine from the reversing section. The shaft 9 of the high pressure turbine carries an ahead rotor element 10 and a reversing rotor element 11. Elastic fluid is admitted to the high pressure, ahead section through a conduit 12 which communicates with an annular steam chest or nozzle chamber 13 and elastic fluid is admitted to the high pressure reversing section through a conduit 14 which communicates with an annular steam chest or nozzle chamber 15. 16 indicates a low pressure turbine comprising an ahead section 17 and a reversing section 18. Ahead section 17 is supplied with elastic fluid through a conduit 19 which communicates with an annular steam chest or nozzle chamber 20 and the reversing section 18 is supplied with elastic fluid through a conduit 21 which communicates with an annular steam chest or nozzle chamber 22. The rotor elements 23 and 24 of the low pressure turbine are mounted on a shaft 25. The exhaust ends of turbine sections 17 and 18 face toward each other and communicate with an exhaust housing 26 which is connected to a suitable condenser 27. 28 and 29 indicate the exhaust conduit for high pressure sections 6 and 7 respectively and they are connected by conduits 30 and 31 to inlet conduits 19 and 21. In the present instance, the turbine structures are shown as being of the impulse type, the rings of buckets being carried by bucket wheels, but it will be understood that this is only by way of example and is to be taken as representing any suitable type of turbine. The shafts 9 and 25 may drive any suitable load or loads. For example, in the case of ship propulsion, they may drive such apparatus as is required in connection with propulsion of the ship.

In operation, elastic fluid is admitted to either the ahead turbine section or the reversing turbine section, depending on which way it is desired to rotate shafts 9 and 25. When it is desired to rotate the shafts in a forward direction, elastic fluid is admitted through conduit 12 to annular nozzle chamber 13 from whence it flows through nozzles indicated at 13^a to the forward turbine section 6. After passing through turbine section 6 the elastic fluid flows by way of conduits 28, 30 and 19 to nozzle chamber 20 from whence it flows through nozzles 20^a to the low pressure turbine section 17. From the low pressure turbine section elastic fluid exhausts into exhaust housing 26 from whence it passes to condenser 27. When the high pressure turbine sections are in operation, the supply of elastic fluid to the reversing sections is, of course, shut off. When it is desired to operate shafts 9 and 25 in reversing direction, elastic fluid is shut off from the ahead section 6 of the high pressure turbine and is admitted to the high pressure reversing section 7 by way of conduit 14, the exhaust from the high pressure

section passing by way of conduits 29, 31 and 21 to the reversing section 18 of the low pressure turbine. After flowing through the low pressure reversing section the elastic fluid exhausts into housing 26 from whence it flows to condenser 27.

A turbine installation of the foregoing type is well known in the art and is to be taken as typical of any suitable arrangement.

It has been found that when a turbine rotor is running in reverse direction it tends to establish a strong current through the blades, creating a backward circulation through the rotor buckets and according to the present invention, I provide suitable means for maintaining such a circulation backwards through an idle running rotor, thereby taking advantage of what may be termed the pumping action of the blades to create a circulation which will serve to cool the rotor through which the flow is taking place.

In carrying out my invention, in accordance with the arrangement shown in Fig. 1, I connect nozzle chamber 13 to condenser 27 by means of a conduit 32 and nozzle chamber 15 to condenser 27 by means of a conduit 33. In each of conduits 32 and 33 I provide valves 34 and 35 respectively which are normally biased to open positions by suitable means such as the springs 36 and 37. Valves 34 and 35 are adapted to be closed by the steam pressure whenever steam is admitted to chambers 13 or 15. To this end valves 34 and 35 may be provided with suitable stops 34^a and 35^a which limit their opening to such an extent that when any appreciable amount of elastic fluid starts to flow through them the difference in pressure on opposite sides of the valves will be such as to cause them to close.

The operation is as follows: Assume that elastic fluid is being supplied to the high pressure turbine section 6 and that the supply of elastic fluid is shut off from the high pressure reversing section 7. The pressure of the elastic fluid in annular chamber 13 will effect a closing of valve 34 against the biasing action of spring 36. This disconnects chamber 13 from condenser 27. No elastic fluid pressure being present in chamber 15, spring 37 will hold valve 35 open. There is now a path of flow for exhaust elastic fluid from housing 26 backwards through reversing turbine section 18, thence through conduit 31 to the exhaust end of reversing turbine section 7, thence backwards through turbine section 7 and through conduit 33 to condenser 27. The reversing turbine rotors 24 and 11 are running idle in their casings and in a direction opposite to their normal direction or rotation and will create a pumping action which will set up a continuous flow of elastic fluid through

the path just described, which elastic fluid will serve to cool the rotors 24 and 11. When it is desired to operate the reversing turbine sections, the supply of elastic fluid to the high pressure ahead section 6 is shut off and that to the high pressure reversing section 7 turned on. When the supply of high pressure elastic fluid is shut off to chamber 13 the pressure therein will be relieved and spring 36 will open valve 34, thus connecting inlet chamber 13 to condenser 27. On the other hand, the admission of elastic fluid to chamber 15 will build up a pressure therein which will effect the closing of valve 35. It will thus be seen that chamber 13 is then connected by way of conduit 32 to condenser 27, while chamber 15 is disconnected from condenser 27. Turbine rotors 23 and 10 are now run in a direction the reverse of their normal direction and will by their pumping action set up a flow of elastic fluid from housing 26 backwards through turbine 17 to chamber 20 thence by way of conduit 30 to the discharge end of turbine section 6, then through turbine section 6 to chamber 13 and through conduit 32 to condenser 27 in a manner already described in connection with the reversing turbine sections.

It will thus be seen that whenever elastic fluid is supplied to the ahead turbine section 6, the path of flow for cooling fluid for the ahead turbine sections is shut off, and at the same time the path of flow for cooling fluid for the reversing turbine sections is established. Likewise, whenever elastic fluid is supplied to the reversing turbine section 7 the path of flow for cooling fluid for the reversing turbine sections is shut off and that for the ahead turbine sections established.

The exhaust elastic fluid taken from housing 26 is particularly advantageous for cooling because it contains more or less moisture which, of course, is capable of taking up a large amount of heat when being converted into steam. Furthermore, it will be seen that by my invention I utilize for cooling purposes elastic fluid which has passed entirely through the turbine sections and from which all useful energy has been extracted. The elastic fluid used for cooling purposes does not, therefore, detract from the efficiency of the installation.

In Fig. 2 I have illustrated a modified form of valve structure for effecting the connections between the ahead and reversing sections of the high pressure turbine and the condenser. In this figure passages 40 and 41 are connected to the ahead and astern inlets of the high pressure turbine sections; that is, to inlets corresponding to the inlets 13 and 15 of Fig. 1. Passage 42 is connected to the condenser after the manner of pipes 32 and 33 in Fig. 1. 43 and 44 are suitable valves carried by a common stem 45, the ar-

angement being such that when valve 44 is closed, valve 43 is open and vice versa. 46 is a hand lever which may be supplied for operating the valves manually whereby the 5 freedom of the valve structure may be tested. The operation of the arrangement shown in Fig. 2 will be obvious from the description of the structure of Fig. 1. It will be clear that whenever elastic fluid is admitted 10 to the high pressure ahead turbine section, elastic fluid pressure will close valve 43 and open valve 44, thereby connecting the admission end of the high pressure reversing turbine section to the condenser. On the other 15 hand, when elastic fluid is admitted to the high pressure reversing turbine section, the pressure will close valve 44 and open valve 43, thus connecting the inlet end of the high pressure ahead turbine section to the condenser. The action of the turbine rotor or 20 rotors in effecting a circulation to cool the idle running rotors is the same as that already described in connection with Fig. 1.

In accordance with the provisions of the 25 patent statutes, I have described the principle of operation of my invention, together with the apparatus which I now consider to represent the best embodiment thereof; but I desire to have it understood that the 30 apparatus shown is only illustrative, and that the invention may be carried out by other means.

What I claim as new and desire to secure by Letters Patent of the United States, is,—

1. The combination with an elastic fluid 35 turbine structure comprising high pressure ahead and reversing sections, low pressure ahead and reversing sections, the ahead sections and the reversing sections being each connected in series, and a housing into which the low pressure sections exhaust, of valve 40 means for connecting the inlets of the high pressure ahead and reversing sections to a region of low pressure whereby the blading of the idle-running sections may pump elastic fluid backward through such sections in 45 series to the region of low pressure.

2. The combination with a compound turbine 50 structure comprising high pressure ahead and reversing sections and low pressure ahead and reversing sections, the ahead sections and the reversing sections being each connected in series, and a housing into which the low pressure sections exhaust, of 55 conduits connecting the inlets of the high pressure ahead and reversing turbine sections to the region of the exhaust housing; and valves in said conduits which are actuated by the pressure of elastic fluid admitted to the high pressure turbine sections.

In witness whereof, I have hereunto set my hand this sixth day of May, 1921.

REGINALD FRANCIS HALLIWELL.
